UNITED STATES PATENT OFFICE.

ISRAEL HOGELAND, OF INDIANAPOLIS, INDIANA, ASSIGNOR TO HIMSELF AND GEO. P. ANDERSON, OF SAME PLACE.

MACHINE FOR PRESSING AND MOLDING CLAY INTO TILES AND OTHER ARTICLES.

SPECIFICATION forming part of Letters Patent No. 224,015, dated February 3, 1880.

Application filed December 27, 1878.

To all whom it may concern:

Be it known that I, ISRAEL HOGELAND, of Indianapolis, in the county of Marion and State of Indiana, have invented a new Machine for Pressing and Molding Clay into a Variety of Irregular Forms, of which the following is a description, reference being had to the accompanying drawings.

Prior to my invention I am not aware that any machine ever was constructed whereby clay that is mixed in and pressed or forced out of any ordinary tile, brick, or pug mills could be formed or molded into various articles of irregular form as the clay leaves the mouth of the mill.

The object of my invention is to construct the dies at the mouth of a tile, brick, or pug mill so as to permit them to be adjusted to various sizes as the clay is being forced through them, and thus produce articles of clay having a variety of forms, such as coffins, irregular boxes, pipes, and moldings.

My invention consists in the new construction, arrangement, and application of devices, all of which, singly or combined, are deemed essential in my newly-organized machine, whereby the clay, as it is forced from the mouth of a tile, brick, or pug mill, may be formed into articles of various forms, as will be hereinafter fully described and set forth.

In the accompanying drawings, in which like letters of reference in the different figures indicate like parts, Figure 1 represents an ordinary tile, brick, or pug mill embodying my invention. Fig. 2 represents one form of movable or adjustable dies. Fig. 3 represents a coffin as one form in which the clay may be formed as it is forced through the adjustable dies. Fig. 4 represents a longitudinal section of a tile-mill, showing the manner in which the clay is forced through the adjustable dies, by which the irregular sides, ends, and bottom of a coffin are made at one operation of the machine. Fig. 5 represents another form of adjustable dies, by which the irregularly-shaped cover of the coffin is molded.

A D K T represent any ordinary tile, brick, or plug mill, in which clay is mixed and ground to the required fineness, and forced out through

the mouth by means of ordinary mechanical powers, such as are in common use for that purpose, and to which I make no broad claim. At the mouth of the grinder or press-box K are arranged sliding dies O O', which, in this case, are adapted to operate with a lateral motion each way from the center of the press-box—*i. e.*, they slide in the grooves s below and l above, as shown in Fig. 1. At each side of the press-box, or in any other convenient place, are arranged slides E, which operate in suitable guides, such as are shown at a d, the slides E being provided with longitudinal grooves b b, that operate on the slide a to prevent lateral motion; and the cleat J is attached to the side of the box K, leaving the space d between it and the base D for the inner edge of the slide E to operate in, thus preventing the slide from motion up or down. The two slides E E are united together by the bar F, so that they travel together.

Immediately under the mouth of the press-box or grinder is a table, H, which may be made of the ordinary form—*i. e.*, rollers with canvas cover, or in some other form, so as to form a support for the clay as it is forced from the grinding-box.

Each of the slides E are provided with grooves C, or raised projections, which are designed to conform with the irregular shape of the article that is to be produced from the clay. The particular form of groove or guide for moving the dies shown in the drawing is that of each side of a coffin.

Each movable die O is provided with a stud and roller, p v, that operate in the groove C of the slide E, and the two dies O O' are made to overlap each other, and each die is provided with an opening, P P', corresponding to the shape of each side of the coffin and the bottom, as shown in Figs. 1 and 2.

When the slides E are closed up so that the bar F is close to the mouth of the press-box, then the rollers r at each end of the sliding dies O are at the head end of the guides or grooves C, and the side openings, P', of the overlapping sliding dies are as close together as they are designed to go by that pattern of groove or guide C in the slides. When the

slides E E and the bar F move forward the dies O O' gradually open to the widest part, and then close as the rollers r approach the other end of the guide or groove C. Thus the 5 movable dies are permitted to open and close as the slides E E move to or from the press-box, and form a means of forming clay into irregular objects.

The cross-bar F may be provided with a 10 pattern-block, G, that can be used for forming the front end of the first coffin, as shown in Fig. 4; or it may be dispensed with, and the clay that forms the end of the coffin may be cut off at the required taper. The block n 15 may also be inserted in front of the sliding dies O when the coffin is of full length, and held in position by the swinging block R while the clay is forced between the block n and dies O O' to form the other end of the 20 coffin, after which the block R, which is attached to the hinged arm W, is to be turned up and the block n be removed, after which the end of the coffin may be cut from the clay in front of the dies and removed for baking. 25 The movable dies shown in Fig. 5 are designed to lap by each other, the same as the dies in Fig. 2, and are provided with curved openings P, that conform to the shape of the coffin-lid. The dies are opened and closed by 30 a pattern-guide formed in the slides E, similar to that shown in Fig. 1, whereby the dies are opened and closed and the irregular form of the cover produced.

The operation of my new machine is as follows, 35 to wit: The sliding dies O O', having the required shape of openings to form the article desired, are first placed in the slide-grooves s l; then the slides E E, having the guide or groove e corresponding to the irregular form of the 40 article to be produced, are arranged to operate in the guides a d. The slides E E and bar F are then moved up close to the mouth of the press-box, and the clay is then forced through the variable opening P P' of the movable die. 45 As the clay comes in contact with the bar F the slides E E are forced away from the dies, either by the clay or mechanical devices, (not shown,) and at the same time the dies O O' are gradually opened and closed by the rollers r moving in the guides C until the slide E has reached the end of its stroke. Thus the 50 clay is made to conform to the variable opening in the dies, and the front end, sides, and bottom of a coffin are produced of the desired 55 shape. The block n may then be introduced in front of the dies, and held there by the block R until the clay is forced into the space between the block n and dies O, thus forming the end of the coffin, which is separated from 60 the clay next to the dies by cutting at the line m, Fig. 4, when the coffin is ready for removal. The projecting rib i i at the top of each side opening, P', of the dies causes a nice groove to be formed along the upper edge of the sides 65 of the coffin to receive packing when the cover

is placed therein, thus providing a means of making a tight joint.

It will be seen from the foregoing that my new machine is capable of making an endless variety of irregular clay devices by simply 70 varying the style of the openings in the dies and the guide C of the slides, and for irregular moldings the column of clay may run out to any desired length required.

In making some irregular devices it may be 75 necessary to arrange more or less adjustable dies, and to arrange the die-opening guide-slide in different ways from that shown in the drawings, in order to move the die to correspond with the irregular form of the work produced. 80

What I claim as new, and wish to secure by Letters Patent, is—

1. In a machine adapted to force clay or other analogous substances from its mouth, 85 such as tile, brick, or pug mill, the movable dies O O', arranged parallel to and lapping onto each other, and adapted to move laterally either to or from each other, and having openings or passages in each for the clay to 90 pass through, that conform to the shape of the article to be produced, substantially as shown and described.

2. The mouth of a grinder or press-box provided with one or more movable dies operated by pattern-guides, whereby a variable motion is imparted to said dies for the purpose of opening or closing the passage through which the clay is being ejected, thereby giving the ejected clay an irregular shape in conformity to the pattern used, substantially as set forth and described. 95 100

3. The movable or adjustable dies O O' at the mouth of the grinder or press-box, having openings P P' that conform to the design or 105 shape of the article designed to be molded, combined with a pattern or guide, by means of which one or more of the movable dies are operated and moved, whereby an irregular form is produced to the column of clay, substantially as set forth, for the purpose specified. 110

4. In combination with the movable dies O O', operated by pattern-guides to produce irregular sizes of the column of clay that is 115 ejected, the former-blocks G n and holding-block R, substantially as and for the purpose specified.

5. The mouth of a grinder or press-box provided with cross-slides s l, in which operate 120 the movable dies O O', adapted to make regular or irregular size openings for the clay to pass through, substantially as shown and described.

6. In combination with the former-block n, 125 the holding-block R, substantially as shown and described.

7. In a grinder or press-box provided with adjustable sliding die-plates O O', the slides E E, provided with pattern ribs or grooves C, 130

whereby the dies are opened or closed as the clay is ejected and the slides E moved forward, substantially as and for the purpose specified.

5 8. In combination with a grinder or press-box having adjustable sliding perforated die-plates O O', operated by pattern-slides E E, the table or carriage H for supporting the column of clay, substantially as shown and de-
10 scribed.

In testimony whereof I have signed my name to this specification in the presence of two subscribing witnesses.

ISRAEL HOGELAND.
